US0D1112720S

(12) **United States Design Patent** (10) **Patent No.:** **US D1,112,720 S**
(45) **Date of Patent:** **** Feb. 10, 2026**

(54) **MASK**

(71) Applicant: **DCSTAR INC.**, New York, NY (US)

(72) Inventor: **Ligui He**, New York, NY (US)

(73) Assignee: **DCSTAR INC.**, New York, NY (US)

(**) Term: **15 Years**

(21) Appl. No.: **29/983,254**

(22) Filed: **Jan. 9, 2025**

Related U.S. Application Data

(63) Continuation of application No. 29/882,899, filed on Jan. 20, 2023, now Pat. No. Des. 1,069,102.

(57) **CLAIM**

The ornamental design for a mask, as shown and described.

DESCRIPTION

FIG. 1 is a front view of a mask showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a front, top and right perspective view thereof; and,

FIG. 8 is a rear, bottom and right perspective view thereof.

The broken lines depict portions of the mask that form no part of the claimed design.

1 Claim, 8 Drawing Sheets
